UNITED STATES PATENT OFFICE

149,395

DESIGN FOR A SPORT SHIRT

Daniel Aminoff, Los Angeles, Calif.

Application September 24, 1947, Serial No. 141,565

Term of patent 3½ years

(Cl. D3—25)

To all whom it may concern:

Be it known that I, Daniel Aminoff, a citizen of the United States of America, residing in Los Angeles, county of Los Angeles, and State of California, have invented a new, original, and ornamental Design for a Sport Shirt, of which the following is a specification, reference being had to the accompanying drawing, forming part thereof, wherein the figure is a front elevational view of a sport shirt, showing my new design.

The rear of the sport shirt is identical in appearance to the front shown, except for the omission of the front central borders.

I claim:

The ornamental design for a sport shirt, substantially as shown and described.

DANIEL AMINOFF.
